UNITED STATES PATENT OFFICE.

EDWARD N. BROWN, OF CLEVELAND, OHIO, ASSIGNOR OF ONE-HALF TO JOHN GORDON,
OF EAST CLEVELAND, OHIO.

STEAM-VULCANIZER.

1,151,924.

Specification of Letters Patent. Patented Aug. 31, 1915.

Application filed December 7, 1914. Serial No. 375,784.

To all whom it may concern:

Be it known that I, EDWARD N. BROWN, a citizen of the United States, residing at East Cleveland, in the county of Cuyahoga and State of Ohio, have invented certain new and useful Improvements in Steam-Vulcanizers, of which the following is a specification.

This invention relates to steam vulcanizers, and the invention comprises a vulcanizer member, particularly constructed to superheat the steam generated therein, whereby a rubber article may be quickly, safely and thoroughly vulcanized with the use of a minimum amount of combustible fluid.

In the accompanying drawings, Figure 1 is a plan view of one form of the vulcanizer, and Fig. 2 is a vertical section thereof showing a rubber tire clamped therein. Fig. 3 is a perspective view of the vulcanizer body without the superheating dome. Figs. 4 and 5 are sectional views of a modification of the invention.

The vulcanizer shown in Figs. 1 to 3, comprises a round hollow body 2 of cast metal having a flat bottom 3 and integral arms 4 extending from opposite sides. Clamping of the body 2 upon a rubber article, such as a tire, may be accomplished by any suitable means engaged with arms 4, and a plate 5 having screws 6, and thumbscrews 7 are the clamping auxiliaries commonly used when a flat tire is being vulcanized. The chamber 8 within the body is filled partly with a small quantity of water or other liquid, and a series of pockets or compartments 9 are provided in the closed top 10 of the body to receive a combustible fluid such as gasolene or alcohol. Channels 11 in top 10 provide open communication between the compartments 9 to permit the combustible fluid to flow to a uniform height in all the compartments during filling operations, and an annular flange 12 surrounds the top 10 and prevents overflow or spilling of the combustible fluid in filling the compartments.

A screw-threaded opening 13 is provided in the center of top 10 to receive the threaded hollow stem 14 of a flat round steam dome 15 which overlies the burner pockets 9 in such near relations thereto that the flame from the combustible fluid will impinge and envelop the same. Dome 15 might be an integral part of the body and be of various shapes and forms and still serve the pur-

pose for which it is primarily intended,—that of superheating the steam which is generated from the liquid within the body by the flames arising from the combustible fluid in the compartments 9. The walls of the pockets or compartments 9 extend downward into the liquid within chamber 8, and the first effect of the burning fluid is to convert the liquid into steam and then to superheat this steam after it enters the dome. 60 The superheated steam is diffused uniformly through the vulcanizer interior thereby heating the vulcanizer body uniformly to a high temperature for a sustained period of time so that effective vulcanizing results 65 may be obtained at the bottom thereof without burning or other ill effects to the rubber. Access to the interior of the body 2 is provided by screw plugs 16 at the sides, and dome 15 has a screw plug 17 centrally in its 70 top.

The dome 15 is round preferably, and the space between the dome and the body is open annularly to spread the flame uniformly and also to give convenient access to the bottom of the dome for cleaning and wiping off any soot which may be deposited thereon. A further function of the dome is to allow for the necessary expansion of the steam within the relatively small chamber 8, and 75 its central location and reduced hollow stem causes a uniform diffusion of the steam and heat to the vulcanizer body.

In Figs. 4 and 5, a hollow vulcanizer body 18 is shown which embodies the features 80 hereinbefore described and also includes a hollow right-angled extension 19 having a curved vulcanizing wall 20 with fastening arms 21 at each side thereof, whereby the devices may be supported in an upright vulcanizing position upon a wheel tire T. Curved wall 20 and the flat bottom 3 provide a plurality of vulcanizing surfaces of different forms and permit vulcanizing operations to take place on articles disposed either 85 vertically or horizontally.

What I claim is:

1. A steam vulcanizer comprising a body having independent superimposed compartments for a heating liquid and a combustible fluid, and provided with a steam superheater superimposed above said body. 105

2. A steam vulcanizer having a bottom chamber for a heat diffusing liquid and a burner top for a combustible fluid, in combi- 110

- nation with a superheater in open communication with said bottom chamber.
3. A steam vulcanizer comprising a body having a chamber with liquid therein and provided with an open compartment at its top to hold a combustible fluid, said body being surmounted by a steam superheating dome in open communication with said compartment.
- 10 4. A steam vulcanizer having a sealed chamber for a heat diffusing liquid and provided with a compartment above said chamber to hold a combustible fluid and having a central steam-superheating dome surmounting said compartment.
- 15 5. A steam vulcanizer comprising a hollow body containing a liquid and having an open top surrounded by an annular wall and a steam-superheating dome surmounting said top in open communication with the interior of said hollow body.
- 20 6. A steam vulcanizer having a closed compartment containing a liquid and an open compartment superimposed above said closed compartment and a steam superheat-
- 25
- ing dome surmounting said open compartment and in open communication with said closed compartment.
7. A steam vulcanizer comprising a hollow body with an annular extension at one side and having a plurality of vulcanizing surfaces of different forms, said body containing a heat diffusion fluid and provided with a compartment to hold a combustible fluid and a steam superheater surmounting said compartment and open to the interior of said hollow body.
8. A steam vulcanizer having a plurality of vulcanizing surfaces, a hollow body containing a liquid, an open top for said body to hold a combustible fluid and a steam superheating dome surmounted on said top and open to the interior with said hollow body.

In testimony whereof I affix my signature in presence of two witnesses.

EDWARD N. BROWN.
